FIREARM

Charles H. Barnes, Bridgeport, Conn., assignor to
Remington Arms Company, Inc., a corporation
of Delaware

Application March 18, 1941, Serial No. 383,903

4 Claims. (Cl. 42—3)

This invention relates to firearms and in particular to firearms having gas operated breech blocks.

An object of this invention is to provide an improved mechanism for converting a manually operated firearm into a semi-automatic firearm. A further object is to provide a gun barrel with a movable portion on the muzzle end operated by the force of gas pressure in the barrel, on discharge of the firearm, for effecting automatic operation of the breech block mechanism.

Other objects, features and advantages of the invention will be manifested in the following specification and drawing:

In the drawing:

Fig. 1 shows, partly in section, a side elevation of the barrel portion of a firearm in which a reciprocating tubular magazine transmits motion to the breech. The muzzle blast actuated mechanism is in closed position.

Fig. 2 shows the firearm of Fig. 1 with the muzzle blast actuated mechanism in open position.

Fig. 3 shows an end view of the muzzle and muzzle blast mechanism.

Fig. 4 shows a modification in which the muzzle blast actuated parts are connected to a breech operating action bar instead of a movable magazine tube.

Fig. 5 is an enlarged plan view of the connecting rod of Fig. 1.

Fig. 6 is an end view of the fore-end operated firearm of Fig. 4.

Referring to Fig. 1, 10 represents the usual gun barrel fixedly connected to the forward end of a receiver 11 and provided with the usual front and rear sights 12 and 13 respectively. The receiver 11 contains the well known breech mechanism comprising, in part, a sliding breech block 14, firing pin 15 and cross bar 16 of the magazine-action bar 17; the cross bar 16 is provided with a cam face 18 adapted, on reloading of the firearm, to co-operate with the cam face 19 of the breech block 14. The tubular magazine-action bar 17 is of well known construction having, in this instance, helical indentations 20 for controlling the longitudinal movement of successive cartridges from the magazine to the firing chamber. The functions incident to reloading are effected by reciprocation of the magazine 17, as more fully described in the patent to Pedersen, No. 1,044,568, November 19, 1912. The rearward portion of the magazine-action bar 17 slides in a suitable aperture in the forward end of the receiver 11, and its forward end is slidably sup-

ported by a hanger 21 suitably keyed to the bottom of the barrel 10. The magazine shown and described is for the purpose of illustration only, it being clear that any magazine of similar form and action may be adapted to the purpose of the present invention. A stop collar 22 is secured to the forward end of the magazine by fastening means 23 so that when the magazine is in its extreme forward position the collar 22 will abut 5 to the rear of the hanger 21. The collar 22 thus acts as a stop to limit the forward movement of the tubular magazine 17; it also constitutes an abutment for the forward end of a spiral spring 24 carried loosely by and concentric with the 10 tubular magazine 17. The rear end of the spring 24 is positively held against rearward movement relative to the magazine by engaging the forward face of a hanger 25 keyed to the gun barrel 10. A conventional fore-end 26 is provided as a hand 15 grip for supporting the gun barrel, and for the purpose of this invention is firmly attached to the barrel 10 by suitable fastening means such as screws (not shown) received in tapped holes 27, 28, of the fixed hanger 25 and a lug 29, respectively, suitably secured to the barrel 10. The 20 attachment of the fore-end to the barrel in this manner effects a housing for the unhampered reciprocation of the tubular magazine and the free end of the coil spring 24, within the longitudinal bore of the fore-end. At the forward end of the tubular magazine is a substantially 25 solid block indicated generally by numeral 30, having a cylindrical plug portion 31 seated within the open end of the tubular magazine 17 and secured therein by a suitable screw 32; it will be clear that any equivalent means for securing the plug in the end of the magazine may be used. The forward end of the block 30 is bifurcated so as to form two forwardly extending parallel 30 spaced lips or hinge members 33, between which a connecting rod 34 is pivotally supported at its rear end by pivot pin 35. The forward end of the connecting rod 34 is enlarged in cross section as indicated in Fig. 5 and bifurcated as at 36, 37 so as to form a hinge connection 38 with a downwardly projecting tongue 39 formed on the underside of a segmental member or barrel portion 40 of a barrel sleeve indicated generally by numeral 39. The latter is an integral heavy walled 45 cylindrical tube having an end portion 41 which is bored to substantially the diameter of the barrel bore, and an over-bored skirt 42, the forward part of which completely encircles the end of the barrel 10 as clearly shown in Figs. 1 and 3, while 50 the rear part is slotted to form a pair of spaced 55

side plates 42, 42 (see Fig. 3) suitably bowed to conform to the barrel 10 of the firearm and having upwardly extending walls 43, 43 properly spaced to embrace opposite sides of the front-sight base or rib 44 which is integral with or secured to the forward end of the barrel 10. Suitable pins 45 are adapted to be driven through the walls 43, 43 and sight rib 44 to secure the sleeve 39 to the barrel. The downwardly extending spaced wall portions 46, 46 of the aforesaid side plates constitute hinge members between which one end of a lever arm 47 is pivotally supported, as at 48. The portion 40 of the sleeve 39, together with the arcuately surfaced portion 38, comprise, in effect, an extension of the gun barrel 10, being slightly larger in outside diameter but of substantially the same bore. 49 represents a gas chamber formed between the end of the gun barrel 10 and the rear face of the bore of the sleeve portion 40, the gas chamber being shaped, in cross section, substantially as a truncated cone, and including, in part, an inclined wall 50 adapted to act as a pressure surface for initiating the opening of the pivoted barrel portion 38. As shown in Fig. 3, a portion of the bottom wall of the sleeve 40 is cut or milled out to form a slot 52 somewhat wider than the width of the sleeve bore, and substantially one-half the sleeve depth. The aforementioned segmental member or barrel portion 38 is adapted to conform substantially, as shown, to the shape and dimensions of the milled out slot 52 and is displaceably mounted therein. To this end the segment 38 is integrally formed on the free end of the aforementioned pivoted arm 47, whereby pivotal movement of the latter radially displaces the barrel portion relative to the barrel sleeve 40.

It is believed clear that in the operation of the device the force of the expelled gases created by the explosion will pivot the segmental portion 38 downwardly about the pivot 48 of its pivot arm 47 and by the pivotal connection 51 causes the connecting rod 34 to move rearwardly, whereby the tubular magazine 17 will be retracted to its rearmost position against the restraining force of the spring 24. The magazine is associated with the breech mechanism in such a manner, for example, as described in the aforementioned patent to Pedersen, No. 1,044,568, that rearward movement of the magazine effectively actuates the breech block 14 and breech block mechanism whereby the gun is automatically reloaded. After the force effecting the rearward movement of the magazine has been dissipated in compressing the spring 24, the force of compression of the latter returns the muzzle blast actuated elements to their original position whereby the breech is closed, and the gun is again ready to be fired.

Although the above description has related particularly to the adaptation of the device of this invention to a tubular magazine actuated breech block, it is to be clearly understood that the device may be readily used in connection with the action bar of any of the well known fore-end operated firearms, such, for example, as the firearm shown in the patent to Loomis, No. 1,579,177, March 30, 1926. The adaptation of the muzzle blast mechanism to an action bar is illustrated in the modification shown in Figs. 4 and 6, in which 60 represents an action bar connected at its rear end to suitable breech block mechanism comprising, in part, the usual breech block 61 having a cam groove 62 engaged by a pin 63 carried on the extended end of the action

bar 60, whereby reciprocation of the bar 60 actuates the breech block as more fully explained in the aforementioned Loomis patent. The forward end of the action bar 60 projects forwardly closely adjacent the outer walls of the barrel 10 and tubular magazine 64. It will be understood that the magazine 64 is fixedly mounted at its rear end in the receiver 11 and that its forward end is rigidly connected to the barrel 10 by suitable means, such as hanger 65 and release nut 66; consequently there will be no reciprocating movement of the magazine for reloading the arm. The reloading is done by reciprocation of the action bar 60 which in the usual practice is secured to and actuated by the usual reciprocating fore-end or hand grip 67. In the present construction the fore-end 67 is fixed to the barrel 10 as described in connection with the previous embodiment of the invention and the action bar 60 is extended through the fore-end 67 and reciprocates freely therein in a suitable groove 68 formed in the inner surface of the fixed fore-end as shown in Fig. 6. A coil spring 69 is loosely mounted on the fixed tubular magazine 64. A collar 70 is slidably mounted on the magazine and is adapted to act as a stop or abutment for the forward end of the spring 69. A screw 71 or other suitable means is provided for fastening the action bar to one side of the collar 70, whereby rearward movement of the spring 69 will effect compression of the spring on the magazine 64. It will be understood that the rear end of the spring is held against movement relative to its freely movable front end by suitable means which, as shown, may comprise a second stop collar 72 suitably secured to the barrel 10. As in the embodiment of the invention first described, the spring effects a constant restraining force against rearward movement of the action bar 60 and is of sufficient strength to return the breech block mechanism from its open position to its closed position. While the above description has been confined to the structure shown in Figs. 4 and 6, it will be clearly understood that the invention contemplates the use of any desired means for transmitting the motion of connecting rod 34 to the breech. As shown in Fig. 4, the forward end of the action bar extends beyond the magazine supporting elements 65 and 66 and is provided with a reverse bend as shown at 73 so as to be brought substantially into alignment with the hereinbefore described connecting rod 34 to which the forward end of the action bar 60 is pivoted by a pin 74. The position of the reverse bend 73 in the forward end of the action bar 60 is such that the latter may be moved rearwardly without interference with the fixtures 65 and 66.

The operation of the above described modification is believed to be obvious from the previous description of one embodiment of the invention as given in connection with Figs. 1 and 2.

It will be understood that the constructions shown and described represent a desirable form of the invention for accomplishing the objects stated above but that these constructions are only for the purpose of illustrating the invention and are not limiting thereof as other modifications may be made without departing from the invention as defined in the appended claims.

What is claimed is:

1. In a firearm comprising a receiver; breech mechanism housed in said receiver; a barrel fixed to said receiver; a cylindrical sleeve concentric with the muzzle of said barrel; a gas chamber

comprising an annular conical surface in the mouth of said sleeve adjacent the muzzle of said barrel; actuating means for said breech mechanism comprising a spring and a prismatic section of said gas chamber normally held in position concentric with said barrel by said spring and adapted to be displaced by gaseous pressure within said gas chamber; and connections from said prismatic section to said breech mechanism.

2. In a firearm comprising a receiver; breech mechanism housed in said receiver; a barrel fixed to said receiver; a cylindrical sleeve concentric to the muzzle of said barrel, said sleeve having a gas chamber comprising an annular conical surface in the mouth of said sleeve adjacent the muzzle of said barrel and a displaceable prismatic section; and actuating means for said breech mechanism comprising said displaceable prismatic section of said sleeve, a magazine tube reciprocal relative to said barrel and receiver assembly, means connecting said magazine tube to said breech mechanism, a spring carried on said tube, said spring being constructed and arranged to resist the displacement of said magazine tube and normally to hold the prismatic section of said sleeve concentric with the barrel, said prismatic section being displaceable by gas pressure within said gas chamber, and a link connecting said prismatic section to the magazine tube.

3. In a firearm comprising a receiver; breech mechanism housed in said receiver; a barrel fixed to said receiver; a cylindrical sleeve concentric to the muzzle of said barrel, said sleeve having a gas chamber comprising an annular conical surface in the mouth of said sleeve adjacent the muzzle of said barrel and a displaceable prismatic

section; and actuating means for said breech mechanism comprising said displaceable prismatic section of said sleeve, a magazine tube fixed to said barrel and receiver assembly, an action bar, means for guiding said action bar on said tube, means connecting said action bar to said breech mechanism, a spring carried on said tube, said spring being constructed and arranged to engage said action bar guide means to resist the displacement of said action bar and normally to hold the prismatic section of said sleeve concentric with the barrel, said prismatic section being displaceable by gas pressure within said gas chamber, and a link connecting said prismatic section to the action bar.

4. In a firearm comprising a receiver; a breech mechanism housed in said receiver; a barrel fixed to said receiver having a front sight; a cylindrical sleeve concentric with the muzzle of said barrel, said sleeve comprising spaced upwardly extending walls adapted to cooperatively engage said front sight for securing said sleeve to the muzzle of said barrel, a gas chamber comprising an annular conical surface in the mouth of said sleeve adjacent said barrel muzzle and a displaceable prismatic section pivotally supported on the underside of said sleeve; and actuating means for said breech mechanism comprising a spring and said prismatic section of said sleeve, the latter being normally held in position concentric with said barrel by said spring and adapted to be displaced by gaseous pressure within said gas chamber and connections from said prismatic section to said breech mechanism.
